Primary Examiner — Khawaja Anwar*Assistant Examiner* — Julice Seung Eun Oum(74) Attorney, Agent, or Firm — Neustel Law Offices(57) CLAIM

The ornamental design for an exercise machine, as shown and described.

DESCRIPTION

FIG. 1 is a rear perspective view showing my new design;

FIG. 2 is a front perspective view thereof;

FIG. 3 is a top view thereof;

FIG. 4 is a bottom view thereof;

FIG. 5 is a left view thereof;

FIG. 6 is a right view thereof;

FIG. 7 is a front view thereof; and,

FIG. 8 is a rear view thereof.

The broken line portions of the drawings are included to show unclaimed subject matter and form no part of the claimed design.

1 Claim, 5 Drawing Sheets

See application file for complete search history.
